FREQUENCY SHIFT TELEGRAPH
COMMUNICATION

Clarence W. Hansell, Pert Jefferson, N. Y., assignor to Radio Corporation of America, a corporation of Delaware

Application March 6, 1941, Serial No. 381,945

16 Claims. (Cl. 250—8)

This application relates to frequency modulation signalling systems and in particular spaced wave telegraphy systems such as disclosed in Finch Patent No. 2,225,691, dated December 24, 1940, Hansell application Serial No. 324,051, filed March 15, 1940, now U. S. Patent No. 2,293,501, dated August 18, 1942, and Hansell application Serial No. 395,556, filed May 28, 1941, now U. S. Patent No. 2,339,851, dated January 25, 1944.

In my two applications I have described combinations of equipment for carrying out radio telegraph communication by means of frequency shift keying at the transmitter. In this kind of frequency shift system the frequency of an oscillation or other wave source is keyed between two values one of which represents marks and the other of which represents spaces. In this mode of communication the transmitted power is approximately equivalent to that which would be obtained if two ordinary telegraph transmitters, on different frequencies, were employed to carry the same messages simultaneously by turning on the power of one transmitter when the other is turned off and vice versa.

In my application Serial No. 324,051, filed March 15, 1940, I have shown that, if this type of communication is carried out with suitable equipment, a very worth while reduction in the effects of signal elongations and distortions, due to presence of multiple signaling paths of different time delay, may be obtained. To obtain full advantage of the system, for reducing multipath effects, the amount of frequency difference between the two signaling waves should be greater than the value of the highest required signaling frequency.

To obtain the greatest benefit from frequency shift signaling both from the standpoint of reducing multipath distortions and of reducing the effects of noise, it is desirable that the amount of frequency shift be made quite large in proportion to the highest equivalent modulation frequencies required to reproduce the signals.

In long distance short wave radio communication the transmitters are frequently used alternatively for either telegraph, facsimile or telephone communication. Reasonably satisfactory telephony, or program transmission, requires a modulation frequency band of about 6000 cycles and a corresponding double side band space of 12,000 cycles. It has been common practice to space transmitters 15,000 cycles apart, which allows a tolerance of plus or minus 1500 cycles from assigned frequencies before there can be an interfering overlapping of frequencies transmitted by

one transmitter into the frequency band assigned to another transmitter.

Under these circumstances it is reasonable to assume that, when we employ frequency shift telegraphy, we may permit frequency shifts which are large enough to occupy a total frequency band of up to 12,000 cycles.

In radio telegraph practice a common future traffic requirement may correspond approximately to an assumed keying rate of 28.5 letters or time spaces per second, or 1710 letters or time spaces per minute, in seven unit printer code systems such as disclosed by J. B. Moore and R. E. Mathes in their United States Patent No. 2,183,147, dated

10 December 12, 1939. This would correspond to the use of six time division multiplex channels each working at a rate of about 300 characters, or 60 five-letter words, per minute over the one radio circuit. This method of multiplexing is described in a paper by J. L. Callahan, R. E. Mathes and A. Kahn, entitled, "Time division multiplex in radiotelegraphic practice," which appears in "Proceedings of the Institute of Radio Engineers" for January, 1938.

15 20 25 For this signaling speed and number of channels the signal pulses occur at a rate of

$$(7 \times 6 \times 300) \div 60 = 210$$

per second or, say, approximately 200 per second.

30 35 To reproduce these pulses requires a modulation rate corresponding to 100 cycles per second plus harmonics of 100 cycles up to and including, say, the fifth harmonic, or 500 cycles per second. This modulation rate is much less than that which would be required to occupy all of the available frequency band assigned to each transmitter.

40 In widening the frequency band in accordance with the inventions disclosed in my applications referred to, to obtain a greater reduction in multipath distortion and a greater suppression of the effects of noise and interference it is necessary to keep in mind other phenomena may be encountered which detract from the expected improvement.

45 50 55 For example, widening the frequency band occupied by the signaling currents or waves reduces the effects of noise by an amplitude ratio proportional to the increase in spacing between the two transmitter carrier frequencies only so long as the transmitter carrier current reaching the frequency shift detector in the receiver remains considerably stronger than the peak value of the noise and interference. In practice it may be stated that the initial interfering current components should not exceed in combined instant-

taneous amplitude a value half the amplitude of the received transmitter carrier current, at the frequency modulation detector, for significant intervals of time or the high gain in signal to noise ratio, due to increased frequency shift, begins to be reduced. When the width of the frequency band of the receiver is increased, to accommodate a greater transmitter frequency shift, the relative peak value of significant interfering noise increases by an amplitude ratio lying between the ratio of band widths and the square root of the ratio, depending upon the nature of the noise. Consequently, although widening the band occupied usually results in noise suppression the percentage of time during which noise can wipe out the signal is also increased.

In describing my invention reference will be made to the attached drawings wherein Figure 1 is a graph used to illustrate the character of frequency shift wave and the relative maximum amplitudes, and frequency spacing, of the current components thereof in the frequency spectrum for the conditions described in the example of six channels, time division multiplex using seven unit code and about 60 words per minute speed for each of the six channels. Figure 2 is a diagrammatic showing of the essential units of a receiver arranged in accordance with my invention to receive wave energy of the character of that shown in Figure 1 and to improve the signal to noise ratio during such reception. Figures 3 and 4 illustrate the receiver of Figure 2 with circuits added for reducing the effects of unequal fading of signals in the two transmitted frequency bands. Figure 5 illustrates a diversity receiving system employing receivers of the type illustrated in Figures 2 and 3. Figure 6 illustrates by block diagram a transmitter for producing and transmitting carrier shifted keyed wave energy of the nature illustrated in Figure 1 of the drawings.

In examining Figure 1 a significant observation is that the component frequencies of frequency shift current required to reproduce the telegraph signals are not uniformly distributed throughout the band occupied but are grouped around the two transmitter carrier frequencies. There is a relatively large portion (space) in the middle of the frequency band in which energy of signaling current components is very small but in which noise or interference may enter to wipe out the signal at times.

Wave energy of the nature illustrated in Figure 1 may be produced and transmitted by systems such as disclosed in Finch Patent No. 2,225,691, dated December 24, 1940, and in Hansell U. S. application Serial No. 324,051, filed March 15, 1940. A satisfactory means to accomplish this may comprise an oscillation generator with means to shift its frequency an amount sufficient to prevent side band overlap as explained in detail above in connection with Figure 1. In Figure 6 I have shown by block diagram a transmitter for doing this.

In accordance with this invention I also propose to suppress received currents in this unused frequency band, by means of frequency selectivity, so as to suppress noise and interference currents at the input to the frequency shift detector but, at the same time, to combine the currents derived from the two signalling frequency bands into a single chain of amplifier, amplitude limiter and frequency shift detector circuits. One ar-

angement for doing this is illustrated in Figure 2.

In Figure 2 I have illustrated a receiver for frequency shift keyed signals in which energy picked up from the transmitter by means of an antenna 10 is amplified and heterodyned down to a band of intermediate frequencies. The means for accomplishing this may be conventional and may comprise an amplifier and mixer and I. F. amplifier in unit 12 excited by the wave energy received from 10 and by oscillations received from a source in unit 14. Energy at the intermediate frequencies is applied to two band pass circuits 16 and 18 arranged to pass only the required frequency bands around the two intermediate frequency signaling carrier currents (Fig. 1) and to suppress currents of all other frequencies. This reduction in the width of the band used for passing the energy used for recording purposes reduces the total noise power which reaches the frequency shift detector unit thereby improving the initial signal to noise ratio and making it possible to obtain the noise suppression inherent in wide band frequency modulation systems, when the carrier current is higher than the noise, for a much larger proportion of time.

After the two bands of currents have passed through the filters 16 and 18 they are combined again into one circuit and fed to the intermediate frequency amplifier in 20. This amplifier also includes an amplitude limiter. The amplified and limited wave energy of improved initial signal to noise ratio is fed to a frequency shift detector 22. The frequency shift detector 22, and its output amplifier, if one is used, are designed to respond to all required signaling frequencies which, if necessary, may include response down to zero frequency, corresponding to direct current signal output of either polarity. The resulting output current, which usually will be a direct current which reverses polarity when the transmitter frequency is shifted from one value to the other, may be utilized to operate a signal recorder, printer mechanisms or any other suitable terminal receiving equipment at 24. This output current of reversed polarity may also be considered as two currents utilized differentially.

The apparatus used in units 10, 12 and 14 may be conventional and it is believed unnecessary to describe and illustrate the same in detail here. The filters 16 and 18 may be band pass filters of any known type and here again it is believed unnecessary to illustrate and describe details thereof. In some cases I may replace the band pass filters by high and low pass filters with the cut-offs adjacent each other but separated by the band of frequencies to be attenuated. I may also employ resistance network terminations and coupling amplifier tubes at input and output ends of the filter, if desired, to minimize the effect of one filter on the characteristics of the other.

The intermediate frequency amplifier may be of any approved type as may be the amplitude limiter in unit 20. The same remarks apply to the frequency modulation detector in unit 20 and the recorder in unit 24.

Due to the action of the limiter ahead of the frequency shift detector the current delivered to the detector will possess a center frequency around one transmitter frequency or the other depending upon which transmitter frequency component reaches the limiter with the greater strength. Transition from one frequency to the other will be relatively abrupt in the output from the limiter. Current in the limiter output at one

frequency will be phase modulated by currents at the other frequency, during the transient periods, while multipath is present, as explained in my United States application Serial No. 324,051, filed March 15, 1940. However, in the example of Figure 1, the phase modulation will take place at a rate of 10,000 cycles, which is far above the highest equivalent modulation frequency required to reproduce the signals at the indicated signaling speed. Consequently the modulation will have little significance and may be ignored, or substantially completely eliminated by means of a low pass filter after the frequency shift detector.

Since the receiver of Figure 2 rejects energy received in a broad band between the two signaling bands it is possible to utilize this band for other transmissions, preferably frequency shift transmissions of a similar kind. There may be one, two, or more, working bands for other transmitters between the two bands occupied by the first transmitter. Thus the frequency shift of each transmitter may be much greater than that required to double its frequency band but the frequency space it occupies is only twice that required by the ordinary power on-off keyed transmitter.

Although the system requires twice the frequency band for each transmitter which would be occupied by the older type transmitters it is capable of operation at much higher average speeds because of the reduction in effects of multipath and noise. Consequently, when everything is taken into account it provides more maximum traffic capacity for a given total frequency band than the older systems and, at the same time, improves the reliability with which traffic at any particular speed or number of channels can be maintained.

A further consideration in applying wide frequency shifts is that there may be fading on the two transmitter frequencies which are not alike. This might cause signal unbalances, or even complete drop-outs, when the length of each dot becomes less than the time delay of secondary ionosphere paths. To reduce this possibility I may employ special circuits at the receiver, such as illustrated in Figures 3 and 4, and diversity reception as illustrated in Figure 5.

In the receiver of Figure 2, when no signal current is being received, substantially equal amounts of noise power will pass through the two band pass filters which tend to balance out in the frequency modulation detector. Therefore, within the used output current frequency band, absence of input signal results in substantially no receiver output current. As a consequence, during frequency shift signaling, if both signaling currents fade down below the noise level at the receiver input, the receiver output tends to disappear.

On the other hand, if due to selective fading only one of the signaling currents disappears then the receiver continues to provide a unipolar keyed output due to the remaining keyed current. This unipolar output may be sufficient to maintain traffic in many cases. To utilize it in a reverse current system it is desirable to provide means to derive reverse current signals from the unipolar current signals.

One means for doing this is illustrated in the connections between the detector and recorder elements in Figure 3. According to this scheme the signaling current passes through electrical condensers 30 of dielectric capacity large enough to properly pass the signalling currents at nor-

mal minimum and higher keying speeds. Any unbalance in the two output unidirectional currents of different polarity which lasts for a relatively long time, such as unbalances caused by selective fading, is reduced or stopped by the condensers.

By paralleling each condenser with an adjustable resistance 34 the effect of the condensers 30 in suppressing unbalances can be adjusted 10 and, at the same time, the condensers may be given any desired time constant of response to increasing or decreasing unbalances in the output currents of different polarity.

The arrangement of Figure 4 is another arrangement for accomplishing the same results as Figure 3. In this case a coupling transformer 40 is used to pass on the normal speed signaling currents and adjustable resistances 34 again serve to adjust the time constant of current response to unbalances caused by selective fading. The transformer of Figure 4 may also be replaced by a simple inductive reactance bridged across the output leads from the frequency shift detector in which case resistance in series with 25 the reactance may be adjustable to control the time constant of response to selective fading. However, I prefer the arrangement of Figure 4 because it readily permits impedance transformation between the detector unit and the recorder.

Taking the signal output entirely through condensers as in Fig. 3, or through a transformer as in Fig. 4, makes it impossible for unbalances in strengths of the two carrier currents, when 35 they are on, to cause unbalances in the output current. If one carrier current faded out entirely for a time the other would continue to give output signals with no change in the average or direct current flowing in the utilization circuit.

40 Therefore, the coupling condensers, or transformer prevent any direct current component of final output current which could disturb operation of the following signal handling and recording equipment. If the receiver output is delivered to a recorder, it is undesirable to allow any D. C. component of current which might deflect the recording element against its mechanical stop in a manner to make the signals less intelligible. The recorders usually do have a mechanical stop to cause formation of more nearly rectangular wave records, in spite of noise, as an aid to intelligibility of the record. If no stops were used then the presence of a D. C. current, due to carrier current unbalances, would be somewhat 55 less important but then the record slip would need to be wider or the response to signals would need to be reduced, and intelligibility would be lessened.

If, instead of signal recorders, the signals were 60 fed into printer equipment similar difficulties would be encountered due to the need to prevent biasing of the associated relays and other equipment.

On the other hand, taking signals through condensers or transformers exclusively tends to prevent response to very low signaling speeds, frequently required, or to steady marking or spacing conditions. Therefore, I provide the adjustable shunts around the condensers and transformers to permit adjustment according to conditions of service.

In Figure 5 I have shown a space diversity receiving system. This system makes use of the theory and principle involved in the diversity 75 systems invented by H. H. Beverage and H. O.

Peterson and disclosed in their patents, such as for example: H. H. Beverage et al. Patent #1,819,589, dated August 18, 1931; H. H. Beverage et al. Patent #1,874,866, dated August 30, 1932; H. H. Beverage et al. Patent #1,987,889, dated January 15, 1935; H. O. Peterson Patent #1,863,-695, dated June 21, 1932. A similar system has also been disclosed in my Patent #1,803,504 to which the features of the present invention have been added.

In the arrangement of Figure 5 there are indicated three spaced receiving antennas and three receivers, like the receiver of Figure 3, for receiving the same frequency shift keyed transmitted signals. Outputs from the three receivers are combined into one circuit to provide a combined signal of better quality and reliability than can be provided from a single receiver. The combined signal is then utilized to control a carrier current keyer for sending signals over a wire line to a central traffic office where they may be recorded by standard printing telegraph instruments, or ink recorders when manual transcription is employed.

In some cases in association with the present invention I may also prefer to employ frequency diversity to overcome effects of fading, which I may do by phase, frequency or amplitude modulating the two transmitted carrier currents at a frequency higher than the highest required component modulating frequency required to satisfactorily reproduce the transmitted signals. The principles upon which this kind of diversity are based are disclosed in Goldsmith U. S. Patent No. 1,821,383 and in my application Serial No. 324,-052, filed March 15, 1940, now U. S. Patent No. 2,278,779, dated April 7, 1942. I may also add to the diversity receiving system the principles and arrangements disclosed in my application No. 326,129, filed May 27, 1940, now U. S. Patent No. 2,249,425, dated July 15, 1941, for making the receiver, or receivers, with strongest signal input deliver greater fractions of the total signal output.

In all of the arrangements of Figures 2 to 5, inclusive, and in other arrangements like them, I contemplate employing automatic tuning control of the type described in my application No. 395,556, filed May 28, 1941.

I claim:

1. In a diversity receiving system for wave energy comprising a plurality of keyed carrier currents separated in the frequency spectrum by an amount greater than that required to prevent overlapping of necessary side band currents of each carrier current in the same frequency band at the highest keying frequency, comprising a plurality of receivers each comprising means for rejecting frequencies lying between the bands occupied by the carrier currents as shifted and their necessary side bands, and a frequency shift modulation detector responsive only to all the necessary frequency shift modulation components of the signalling currents, and means for combining the outputs of all of said detectors.

2. The method of communication by frequency shift keyed carrier currents with reduction of noise and multipath distortion including the following steps, producing a substantially fixed frequency shift of the keyed carrier from one position in the frequency spectrum to another position in the frequency spectrum separated from said first position by a band of frequencies greater than the sum of half the necessary side bands of said carrier in each of the positions to which

the carrier is shifted at the maximum rate at which it is shifted, transmitting the wave energy so keyed and shifted, receiving the transmitted wave energy, producing currents representing the received energy, amplifying the produced currents while rejecting currents of frequencies lying between the bands of produced currents representing the necessary side bands of the carrier in its shifted positions, passing the currents not rejected through a common path and subjecting the currents passed by the common path to frequency shift demodulation.

3. The method of communication by frequency shift keyed carrier currents with reduction of noise and multipath distortion including the following steps, producing a substantially fixed frequency shift of the keyed carrier from one position in the frequency spectrum to another position in the frequency spectrum separated from said first position by a band of frequencies greater than the sum of half the necessary side bands of said carrier in each of the positions to which the carrier is shifted at the maximum rate at which it is shifted, transmitting the wave energy so keyed and shifted, receiving the transmitted wave energy, producing currents representing the received wave energy, amplifying the produced currents while rejecting currents of frequencies lying between the bands of produced currents representing the necessary side bands of the carrier in its shifted positions, limiting the amplitude of the currents not rejected, and subjecting the limited currents to frequency shift demodulation to derive direct current which reverses polarity as the carrier shifts from one position to another position.

4. The method of communication by frequency shift keyed carrier currents with reduction of noise and multipath distortion including the following steps, at the transmitter producing a substantially fixed frequency shift of the keyed carrier from one position in the frequency spectrum to another position in the frequency spectrum separated from said first position by a band of frequencies greater than that required to prevent overlapping of necessary side bands in each of the positions to which the carrier is shifted at the maximum rate at which it is shifted, transmitting the wave energy so keyed and shifted, at the receiver producing currents representing the transmitted wave energy, amplifying the produced currents while rejecting currents of frequencies lying between the bands of currents representing the necessary side bands of the carrier in its shifted positions, translating currents not rejected in a common path, limiting the amplitude of the translated currents and subjecting the translated currents to frequency shift demodulation.

5. In a communication system using a transmitted carrier wave shifted in frequency by signals from one substantially fixed frequency to a second substantially fixed frequency, separated from said first frequency by an amount such that the wave in its different positions may be subjected to selective fading, an amplifier for picking up said wave and deriving therefrom currents correspondingly shifted in frequency, filters coupled with said amplifier for passing the currents corresponding to the carrier and its necessary side bands in said two positions, a frequency shift detector coupled to said filters for demodulating the currents passed by said filters to derive therefrom direct currents which reverse polarity as the carrier is shifted from one position to the

other, said demodulator having an output wherein said direct currents are differentially utilized and are, in effect, bi-polar currents, and means in said output for preventing uni-polar currents from being produced in the event of selective fading which reduces the value of the carrier in one of its positions.

6. In a communication system using a transmitted carrier wave shifted in frequency by signals from one substantially fixed frequency to a second substantially fixed frequency, separated from said first frequency by an amount such that the wave in its different positions may be subjected to selective fading, an amplifier for picking up said wave and deriving therefrom currents correspondingly shifted in frequency, filters coupled with said amplifier for passing the currents corresponding to the carrier and its necessary side bands in said two positions, a current amplitude limiter coupled to said filters, a frequency shift detector coupled to said limiter for demodulating the currents passed by said limiter to derive therefrom direct currents which reverse polarity as the carrier is shifted from one position to the other, said demodulator having an output wherein said direct currents appear, which currents are, in effect, bi-polar currents, a recorder and connections coupling said output of said demodulator to said recorder and reactance in said connections for preventing uni-polar currents from being produced and supplied to said recorder in the event of selective fading, which reduces the value of the carrier in one of its positions.

7. In a communication system, means for producing keyed carrier currents shifted through a frequency range greater than that required to prevent overlapping of necessary side band currents of each carrier current in the same frequency bands, circuits for transmitting said carrier currents, a receiver energized by said transmitted currents, filters at said receiver for rejecting frequencies lying between the bands occupied by the carrier currents and their necessary side bands, a recorder, a frequency shift detector coupled to said filters for demodulating the currents passed by said filters, said detector having an output wherein is produced direct current the polarity of which reverses as the carrier currents are shifted in frequency, connections for impressing said direct current on the said recorder, and reactances in said connections between said recorder and said output for maintaining substantially equal said direct currents of opposed polarity in the presence of selective fading of the carrier in the range through which it is shifted.

8. A communication system as recited in claim 6 wherein said reactance is a transformer having a primary winding coupled to the demodulator output and having a secondary winding coupled to the recorder.

9. A system as recited in claim 6 wherein said reactance is a transformer having a primary winding coupled to the demodulator output and a secondary winding coupled to the recorder and wherein a resistance connects one end of the primary winding to one end of the secondary winding and a second resistance connects the other end of the primary winding to the other end of the secondary winding.

10. A system as recited in claim 6 wherein said reactance comprises a condenser in each connection between the demodulator output and said recorder.

11. A system as recited in claim 6 wherein said reactance comprises a condenser in each connection between the demodulator output and the recorder and wherein a resistance is connected in shunt to each condenser.

12. The method of communication by frequency shift keyed carrier currents with reduction of noise and multipath distortion including these steps, at the transmitter producing a carrier and shifting the frequency of the carrier in accordance with signals between two frequencies spaced from each other by a frequency band greater than that required to prevent overlapping of necessary side band currents, of the carrier current in each of its positions, which band of frequencies is at least several hundred cycles wide, transmitting the wave energy so shifted in accordance with signals, at the receiver rejecting currents of frequencies lying between the bands occupied by the carrier current in its shifted positions and the necessary carrier side bands, limiting the amplitude of the remaining shifted carrier and side bands and detecting the said shifted carrier to recover the signals.

13. The method of communication by frequency shift of carrier currents, keyed in accordance with signals, with reduction of noise and multi-path distortions including these steps, at the transmitter producing a frequency shift of the keyed carrier currents from a marking frequency to a spacing frequency separated from the marking frequency by a band of frequencies substantially greater than that required to prevent overlapping of necessary side band currents

35 of each carrier current in the same frequency band at the maximum keying rate, transmitting the wave energy so shifted, at the receiver receiving the transmitted wave energy, and selectively separating the marking frequency and its necessary side bands from the spacing frequency and its necessary side bands for recording purposes while rejecting frequencies lying between the bands occupied by the spacing and marking frequency currents and their necessary side bands.

14. The method of communication by frequency shift keyed carrier currents with reduction of noise and multi-path distortions including these steps, producing a frequency shift of the keyed carrier current from a first frequency to a second frequency separated from said first frequency by a band of frequencies substantially greater than that required to prevent overlapping, in the same frequency band, of necessary side band currents of each carrier current at the maximum keying rate, transmitting the wave energy so shifted, receiving the transmitted wave energy, rejecting currents of frequencies lying between the bands occupied by the carrier currents and their necessary side bands, passing the two carriers and their side bands only through a common path, limiting the amplitudes of the currents passed by said common path and demodulating and recording the limited currents.

15. In a communication system, means for producing wave energy of carrier frequency and shifting the said wave energy in accordance with signals from a first frequency to a second frequency spaced from the first frequency by an amount greater than that required to prevent overlapping of necessary side band currents of the said carrier in its shifted positions at the highest signal frequency, a receiver for said currents comprising selective circuits which reject frequencies lying between the bands occupied by

the carrier current in its shifted positions and its necessary side bands, means for passing said currents through said selective circuits, means for combining the currents passed by said selective circuits, an amplitude limiter connected with said last named means for removing amplitude modulation from the combined currents, and frequency shift detecting means coupled with said limiter.

16. The method of communication by frequency shift keyed carrier currents with reduction of noise and multi-path distortion including the steps of producing wave energy of carrier wave frequency shifted in frequency in accordance with signals from a first frequency to a sec-

ond frequency separated from the first frequency by a band of frequencies such that the transmission characteristics for the carrier in its shifted positions may be different, which band is at least several hundred cycles wide so the necessary carrier side bands occupy a space considerably less than the space between said first and second frequencies, transmitting said carrier wave energy and necessary side bands, receiving and amplifying the carrier wave energy and its necessary side bands while rejecting energy at frequencies lying between adjacent side band frequencies, and rectifying the carrier and side band frequencies not rejected.

15

CLARENCE W. HANSELL.
